UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

CURTAIN-FIXTURE.

1,256,053.

Specification of Letters Patent.

Patented Feb. 12, 1918.

Application filed March 13, 1916. Serial No. 83,745.

To all whom it may concern:

Be it known that I, HARRY H. SCHROYER, a citizen of the United States, and a resident of the city of Chicago, in the county of Cook and State of Illinois, have invented certain new and useful Improvements in Curtain-Fixtures; and I do hereby declare that the following is a full, clear, and exact description of the same, reference being had to the accompanying drawings, and to the numerals of reference marked thereon, which form a part of this specification.

This invention relates to an improved type of adjustable curtain fixture of the spring impelled expansible type adapted for use on window frames provided with curtain guides to receive the ends of the curtain fixture therein. The invention is more particularly adapted for use on car windows, the purpose thereof being to frictionally retain the curtain in any adjusted position without rattling and to permit easy adjustment of the curtain to any point desired, the fixture being adjustable to change the spring tension upon the parts and as well permit use thereof on windows of different width.

It is an object therefore of this invention to construct a curtain fixture which is extensible under stress of resilient members to engage with curtain guides on a window to retain the curtain in any desired adjusted position.

It is also an object of this invention to provide an improved construction of a curtain fixture wherein the parts are adjustable to vary the extension of the fixture as well as the spring stress on the parts, and furthermore provided with centralizing means to insure the guide feet at the ends of the fixture being always disposed parallel to one another and in proper relation to the finger pieces of the fixture for movement in the curtain guides on the window.

It is furthermore an important object of this invention to construct an adjustable curtain fixture operating under stress of resilient means to extend the guide feet of the curtain for engagement with curtain guides on the window casing, and with the members adjustable to adapt the fixture for use on windows of different width, said means further provided with mechanisms for centralizing the guide feet in proper position after adjustment thereof.

It is finally an object of this invention to

construct an improved type of adjustable curtain fixture simple in construction and operation and easy to assemble and connect in place.

The invention (in a preferred form) is illustrated in the drawings and hereinafter more fully described.

In the drawings:

Figure 1 is a fragmentary interior view of a window curtain equipped with a fixture embodying the principles of my invention.

Fig. 2 is a central vertical section partly broken away taken through the curtain fixture detached from the curtain.

Fig. 3 is an interior sectional view at the middle of the curtain fixture.

Fig. 4 is an enlarged fragmentary elevation at one end of the fixture.

Fig. 5 is an enlarged detail of the centralizing latch mechanism of the device.

Fig. 6 is a detail section on line 6—6 of Fig. 5.

Fig. 7 is a detail section on line 7—7 of Fig. 2.

As shown in the drawings:

The reference numeral 1, indicates as a whole a window frame having a sash 2, mounted therein, with curtain guides 3, on each side of the window frame. Connected upon a conventional type of spring roller (not shown) is a curtain 4, and secured within a tubular inclosure or hem formed along the lower edge thereof, is a curtain fixture embodying the principles of my invention. The fixture consists of a long metal tube 5, having slidably engaged through the ends thereof, rods 6, the outer extremities of which are flattened, as denoted by the reference numerals 7, and have riveted on each side thereof flat metallic bars 8, between which at the ends, are journaled rollers 9. The extreme outer ends of the portions 7, of said rods are rounded off and provided with a steel or other metal wear strip 7^a, which projects beyond the line of contact of the rollers 9, affording a frictional engaging surface for contact with the curtain guides 3.

Rigidly secured into the inner ends of each of the rod portions 6, by means of pins 10, are rods 11, the inner extremity of each of which is threaded and engages in a threaded tubular portion 12, of an actuating finger piece 13, each of which projects outwardly through slots in the casing tube 5. Inserted within the casing tube 5, at the central por-

tion thereof, is a sleeve 14, which is slotted in register with the slots in the main casing 5, for projection of the finger pieces 13, therethrough. As clearly shown in Fig. 2, 5 the casing tube 5, is indented at the point denoted by the reference numeral 15, at each end of the sleeve 14, to retain the sleeve positioned therein. Inserted into the casing tube 5, from each end thereof, and seated 10 against the indented portion thereof, are collars 16, through which the rods 11, slidably extend, and coiled about each of said rods 11, is a compression spring 17, one end of each of which bears against the respective collars 15 16. The other ends of each of said compression springs 17, bear against washers 18, which bear upon deformed washers each denoted as a whole by the reference numeral 19, having two indented portions 20, adapted 20 to engage in complementary recesses therefor provided in the inner end of the rod member 6, thrust inwardly by the spring 17, thus affording a spring latching engagement with said rod.

25 Said deformed washer 19, is provided with a horizontally directed bent tail extension 21, which engages slidably in a longitudinal slot 22, provided therefor in the casing tube 5, to prevent rotation of said deformed 30 washer.

The operation is as follows:

When the device is in use attached upon a curtain, in order to adjust the curtain the finger pieces 13, are pressed inwardly toward 35 one another, thus retracting the guide feet 8, toward one another against the compression of the respective springs 17, and permitting easy movement of the curtain to the desired position. When the finger pieces 13, 40 are released, the guide feet 8, are impelled outwardly by the respective springs 17, such that the outer rounded end strips 7^a, as well as the rounded central portion of the bars 8, bear frictionally against the bottom wall of 45 the curtain guides. In the event that the lower end of the curtain becomes tilted in adjusting the same, that is, out of parallel with the window sill, one or the other of the rollers 9, on the guide feed 8, will contact 50 the bottom of the curtain guide, and rolling thereon will cause the curtain fixture to adjust itself to proper parallel or horizontal position in the window frame. If it is desired to change the length or extension of the 55 fixture, either one or both of the rod members 6, is rotated in the tubular casing 5, so that the rod 11, rigidly attached thereto, is threaded inwardly or outwardly, as the case may be, in the tubular portion 12, of the 60 finger piece, to thus change the extension or projection of the rod members 6, in the casing tube 5. It is obvious also that such

a movement changes the stress upon the springs 17.

Return of the guide feet 8, to proper parallel position is always assured, due to the latching and centralizing effect of the deformed washer 19, the indents 20, thereof, clicking into the complementary recesses provided therefor in the inner ends of the rods 70 6, under the stress of the compression spring 17. The deformed washers 19, are prevented from rotating with the rod portions 6, when the same are adjusted, due to the engagement of the tail 21, of each of said 75 washers in the respective slots 22, of the casing tube 5.

I am aware that various details of construction may be varied through a wide range without departing from the principles 80 of this invention, and I therefore do not purpose limiting the patent granted otherwise than necessitated by the prior art.

I claim as my invention:

1. In a curtain fixture of the class described, a tubular casing, slidable means mounted therein adapted to co-act with curtain guides in a window frame, resilient means acting to impel said means normally outwardly, said means rotatable in said casing to change the extension thereof with respect thereto, and mechanisms acting automatically to interlock with said means at predetermined points with reference to said casing to insure proper alignment and disposition thereof for proper co-action with the curtain guides after an adjustment thereof.

2. In a device of the class described, a tubular casing, rods slidable therein, means secured on the ends thereof for co-action with curtain guides on a window frame, rods rigidly secured on the inner end of each of said rods and projecting inwardly within said tubular casing, finger pieces slidably mounted within said tubular casing and having threaded engagement with said latter mentioned rods to permit adjustment thereof with respect thereto, coiled springs disposed around said latter mentioned rods acting to 100 impel the same and said first mentioned rods and said means outwardly from the casing, and latching detent mechanism connected between said coiled springs and said first mentioned rods adapted to latch the same in 105 a predetermined position of adjustment when the same are adjusted.

In testimony whereof I have hereunto subscribed my name in the presence of two subscribing witnesses.

HARRY H. SCHROYER.
